MULTIPLE RECORDING INSTRUMENT

John A. Caldwell, Philadelphia, Pa., assignor to
 The Brown Instrument Company, Philadelphia,
 Pa., a corporation of Pennsylvania

Application June 20, 1942, Serial No. 447,863

26 Claims. (Cl. 234—66)

1

The present invention relates to self-balancing potentiometers, and more particularly to that type of instrument which is capable of rapidly and successively measuring and recording the value of several variable conditions.

The majority of potentiometer instruments known in the prior art are dependent upon the deflection of a galvanometer pointer to indicate a change in the value of the condition. Some cyclically operating mechanism then detects the position of the galvanometer pointer and operates through a relay to position a marking or other exhibiting element, and in some cases to operate a control. Each of these instruments must inherently move the exhibiting element in a series of steps until it is properly positioned. Thereafter, if the instrument is a multiple recorder, some means is used to move the marking element into engagement with the chart and to subsequently connect the instrument to another condition to be measured and recorded.

With few exceptions, a multiple recording instrument is made to measure and record each condition within given periods of time. If the conditions being measured have their values close together a recording operation can not occur until after the given period of time has expired, even though the instrument almost immediately positions the marker. In another type of recording instrument, a record of the value of the condition is made a predetermined number of cycles after the marker is properly positioned. Both types of instruments require an excessive period of time after the marker is properly positioned before the recording operation can take place.

It is an object of my invention to provide a multiple potentiometer instrument which is not cyclic in operation so that the marker may be continuously and rapidly moved to recording position. It is a further object of the invention to provide means to make the record of the value of the condition substantially immediately after the marker is properly positioned, and to immediately thereafter connect the instrument with another condition to be measured.

It is a further object of the invention to provide a potentiometer instrument in which the various calibrating resistances and compensating resistances are located adjacent the slidewire so that they will all be at substantially the same temperature. This insures that the instrument will not be subjected to inaccuracies due to temperature variation between the different parts.

It is a further object of my invention to provide a novel detecting mechanism which will operate

2

immediately after the instrument reaches a balanced condition to actuate the printing mechanism. This detecting mechanism is quiet in operation as well as being positive in the performance of its functions.

It is a further object of the invention to provide a recording instrument in which the chart is easily accessible for inspection and may be readily and quickly changed when a new chart is needed. The chart supply and rewind mechanism is also supplied with novel adjusting means to compensate for irregularly wound rolls of chart paper.

It is a further object of the invention to provide a multiple potentiometer having only two continuously driven parts. These parts are the above mentioned detecting and chart driving mechanisms. The other moving parts of the instrument operate only when a condition change is occurring and when a record is made of the same. It is a further object of the invention to provide a multiple potentiometer instrument in which the various parts are so positioned relative to each other that a compact, readily accessible instrument is provided. The parts are so placed that adjustments and repairs, when necessary, may be made easily and in a minimum of time. The arrangement is such that the casing is no larger than that used for the ordinary potentiometer.

The various features of novelty which characterize my invention are pointed out with particularity in the claims annexed to and forming a part of this specification. For a better understanding of the invention, however, its advantages and specific objects obtained with its use, reference should be had to the accompanying drawings and descriptive matter in which I have illustrated and described a preferred embodiment of the invention.

In the drawings—

Referring first to Figure 1, there is shown schematically a wiring diagram of a potentiometer of the self-balancing type which may be used to indicate, record, and/or control the value of a condition being measured. For purposes of this description it may be assumed that the conditions being measured are temperatures. For this purpose there are shown four thermocouples T, although any other desired number may be used.

The thermocouple T which is responsive to the temperature that is to be measured, operates in conjunction with a potentiometer network which is generally designated at 1 to form a self-balancing potentiometer system. Upon a change in temperature to which the thermocouple is subjected an unbalanced D. C. current in one direction or the opposite is produced depending upon the direction of unbalance of the potentiometer

system. This D. C. current is supplied to an amplifier unit 2 having a vibrator or equivalent device designated at 3 and a transformer designated at 4 which are connected to an amplifying circuit that is not shown. The vibrator 3 preferably is of the form disclosed and claimed in the co-pending application of Frederick W. Side, bearing Serial Number 421,176.

The direct current supplied to the amplifier is converted by the vibrator to a pulsating current of one phase or of an opposite phase depending upon the sense of unbalance of the potentiometer system. This pulsating current is detected by the transformer 4 and is amplified by a vacuum tube system which may take the form of that shown in the copending application of Walter P. Wilis filed December 1, 1941, and having Serial No. 421,173. The current from the amplifier is used for operating a reversible motor generally designated at 5 in one direction or the opposite direction. This motor serves to operate a slide wire assembly to rebalance the potentiometer system and also serves to move an indicating and recording mechanism which will be described in detail below.

The potentiometer network may comprise three resistances, 6, 7, and 8 which are connected in series. These resistances are usually formed of some wire having substantially no temperature resistance coefficient and may be used for calibration purposes. Connected in parallel to these resistances are a battery 9 which may be in the form of a dry cell and a dual vernier rheostat comprising resistances 10 and 11 and electrically connected sliding contacts 12 and 13 which engage with the resistances 10 and 11 respectively. The rheostat may be operated by any suitable type of knob, there being a direct mechanical connection between the knob and the contact 12 and a lost motion connection between the knob and the contact 13. Upon initial movement of the knob, the contact 12 is first moved and then the contact 13 is moved thereby providing a vernier adjustment. The battery 9 and the rheostat are connected in series with respect to each other and in parallel with the resistances 6, 7, and 8. Also connected in parallel with the first mentioned resistances are two other resistances 14 and 15, which are in turn connected in series with each other. The resistance 14 is preferably made of copper or other material having a suitable temperature resistance coefficient and the resistance 15 may be made of manganin having substantially no temperature coefficient of resistance. The resistance 14 operates to compensate for temperature changes at the cold junction of the thermocouple and is so connected into the network that the voltage drop across it is added to the thermocouple E. M. F. The resistance 15 is utilized primarily for standardization purposes and has a resistance value such that the voltage drop across it is equal to the voltage produced by the standard cell.

The slidewire assembly consists preferably of a coil 16 which is wound around and insulated from a core 17. Cooperating with the slide wire is a collector bar 18 which is also wrapped around a core 19. The slide wire and the collector bar are electrically connected by a sliding contact 20 that is driven by the motor 5 to rebalance the potentiometer circuit. The terminals of the slide wire 16 and its core 17 are connected in parallel around the resistance 7.

A two position switch 21 is connected into the potentiometer network and serves the purpose of

performing two functions; namely, for connecting the potentiometer circuit for normal operation (run) and for standardizing the potentiometer system (standardizing). Schematically, this switch may comprise a plurality of switch arms of which arms 22 and 23 are moved together by means of a knob 24. Switch arm 22 carries on it a contact 25 and the switch 23 carries on it a contact 26, which contacts are adapted to engage respectively contacts 27 and 28 that are carried by other arms in the switch assembly. The contact 28 is connected with one lead from one of the thermocouples T. This lead is shown as including a wire 29 which terminates in a cold junction 30 that is located closely adjacent to resistance 14. Connected to the junction 30 is a resistance 31 which has a condenser 32 in parallel with it and a wire 33 that leads to the switch contact 28. The other thermocouple lead runs directly through wire 34 to a second cold junction 35, which is also located adjacent resistor 14, and from there through a wire 36 to the collector core 19.

The switch 21 is shown in the run position. When the switch is in its standardizing position the contact 25 engages a contact 37 and the contact 26 engages a contact 38.

Schematically shown as forming a portion of the amplifier 2 is the transformer 4. This transformer comprises a primary winding 39 which has a center tap 39'. Primary winding 39 is wound around a core structure 41 that also has on it a secondary winding 42 that is connected with the amplifier. A shield is provided between the primary and secondary windings and all of these parts may be cased in a suitable housing.

Also shown in a schematic manner is vibrator 3 which comprises a vibrating reed 43 that normally engages contacts 44 and 45 but which during its vibration will separate first from contact 44 and then from contact 45. The reed is vibrated under the influence of a winding 46 that is connected to a suitable source of alternating current. A permanent magnet 47 is associated with the reed and is used for polarization and synchronizing. This structure is also enclosed in a suitable housing. One end of the primary winding 39 of the transformer is connected by a wire 51 to the contact 45 of the vibrator, while the other end of the primary winding is connected by a wire 50 to the contact 44. The center tap 39' of the primary winding is connected by means of a wire 40 with the contacts 25 and 26 so that it can be connected into the potentiometer circuit. Vibrating reed 43 is connected by means of wires 48 and 49 with the potentiometer circuit between resistances 14 and 15. The effect is that a circuit is completed through the thermocouple, the vibrator and the transformer to the potentiometer circuit, and in effect, the vibrator and transformer serve substantially the same function as a galvanometer in an ordinary potentiometer circuit.

From time to time it becomes necessary to standardize the potentiometer and readjust the contacts 12 and 13 to compensate for the decrease of the voltage of battery 9. To this end a standard cell 52 is connected into the potentiometer circuit by means of a wire 53 that connects this cell with contact 37. When the switch 24 is in its lower or standardizing position, the standard cell is connected through the transformer and vibrator by means of the wires 40, 48, and 49 so that it is placed in parallel around resistance 15. The same movement of the switch 24 brings contacts 26 and

38 into engagement to connect conductors 40 and 54. This places a resistance 55 in shunt around the vibrator and transformer.

In the operation of the potentiometer system 5 the battery 9 places a potential drop across the slide wire 16 a portion of which, depending upon the position of contact 20, is opposed by the thermocouple voltage. When the potentiometer is in balance no current is flowing through the thermocouple circuit, but if the temperature which is being measured by the thermocouple then connected in circuit changes, the thermocouple voltage will change and current will flow in one direction or the other through the potentiometer circuit to set up an alternating potential in the secondary winding 42 which is in phase or 180° out of phase with the alternating supply voltage. This alternating potential is amplified and used to control the operation of the motor 5 in the proper direction to move contact 20 to rebalance the potentiometer circuit. If, for example, the temperature should increase, the thermocouple T then in circuit would produce an increased E. M. F. and cause a current flow through the potentiometer circuit. This current flow will go through wire 29, cold junction 30, resistance 31, wire 33, contacts 28, 26, and wire 40 to the center tap 39' of the transformer winding 39. From here the current will flow either through the upper or the lower half of this winding, depending whether the contact 45 or 44 is then engaging the reed 43 and through wires 48 and 49 to the potentiometer circuit. This produces an alternating potential in the transformer secondary 42 of one phase with respect to the supply that is amplified by the amplifier to control the operation of the motor 5 in the proper direction to rebalance the potentiometer circuit. If the temperature had decreased, current would flow in the opposite direction or through wires 49 and 48 to the vibrator 3 and from the transformer through wire 40 creating an alternating potential in the transformer winding 42 of the opposite phase with respect to the supply which is amplified to control the operation of the motor 5 in the opposite direction. It will be noticed that the motor 5, as illustrated, is a rotating field motor that has a squirrel cage rotor with interconnecting bars. Two of the opposite fields of the motor, the power windings, are connected across the supply lines 62 with a condenser 56 in one of the leads. The other opposite fields of the motor, the control windings, are connected to the output of the amplifier 2, and have a condenser 57 in parallel with them. Each pair of the motor fields is connected in series. When the voltage and current through the motor control windings lag the voltage and current in the power windings the motor will rotate in one direction. When the voltage and current in the control windings lead those in the power windings, the motor will rotate in the opposite direction. The amplifier shifts the phase of the current of the motor control windings so that the motor will rotate in the proper direction. As the motor rotates it drives a pinion 258 integral therewith that engages a gear 58.

Attached to, and movable with the gear 58 is a pulley 59 around which is wrapped an endless cable 60 connected to contact 20 so that as the motor rotates, the contact will be moved in one direction or the other to rebalance the potentiometer circuit in a manner above described. One end of the cable 60 runs over a pulley 145 that is carried by an arm 150 pivotally mounted at 151 and biased by a spring 152 to take

up the slack in the cable. The other end of the cable runs around a pulley 148 which has frictionally attached to it a detector member 61. This detector member is used in conjunction with other parts to be later described to detect balance of the potentiometer or non-movement of the cable, to actuate the marking mechanism that records the value of the temperature being measured and to simultaneously connect the instrument to another thermocouple.

The amplifier 2 is connected to the line by suitable leads which are shown at 62, and may be disconnected from the line by a double pole switch 63. There is also disclosed a chart driving motor 64 which may be a rotating field motor of the same type as the motor 5. This motor also has two of its fields connected directly to the leads 62 and the other two connected to these leads by a switch 65. With this arrangement the chart motor 64 may be deenergized while the potentiometer system is still energized, but the motor is always stopped when the potentiometer is deenergized.

All of the instrument mechanism, including the parts which have been described above are located within a casing 66 that may be a casting or sheet metal as desired. This casing has provisions on it whereby it can be mounted in an instrument panel or it may be mounted against a wall. Such provisions are old in the art, and their details are not pertinent to the present disclosure. The casing is provided with a door 67 (Fig. 3) which is hinged at 68 to its right-hand side. This door is provided with a knob 69 that serves to control a latch (not shown) and may have in it a lock so that the instrument may be closed against unauthorized tampering. The door has a window 70 in it through which a chart, a scale and an indicating pointer may be seen.

Located within the casing are various of the parts which have been described. For example, in Figure 6 there is shown a view of the casing 66 with the potentiometer mechanism removed. It will be seen that the amplifier 2, having the vibrator 3 and the transformer 4, is mounted in the casing on the right-hand side against the rear wall. The battery 9 is mounted against the back wall as is the standard cell 52. Suitable terminal blocks for the various connections within the instrument itself and to the thermocouples are also mounted on the back wall of the casing.

A swinging frame 72 is hinged at 71 to the left-hand side of the casing. This frame is mounted so that it can be swung completely out of the casing but may be locked into position in the casing by means of a latch 73 of the type shown in Williams Patent 2,283,304 issued May 19, 1942, which cooperates with a latch plate 74 attached to the right-hand side of the casing. This latch is actuated by a knob 75. The frame carries on it supporting members for all of the resistors that have been described above, as well as the chart, the printing mechanism, the detecting mechanism and the switches for the chart driving motor and the current supply to the amplifier. The frame 72, as shown in Figure 3, is formed with a pair of mechanism supporting ends and a connecting part, that also has various parts mounted upon it. For convenience in the following description, the left end of frame 72 in Figure 3 will be referred to as 72A while the right end will be referred to as

72B. The connecting part will continue to be referred to by the numeral 72.

On the upper front part of the frame 72 is a small sheet metal casing 76 that extends across the width of the instrument. This casing has in it supports 77 for various of the resistors as best shown in Figure 2. Each of these supports is attached to a plate 78 that may be bodily removed along with the resistors if it is desired to change the range of the instrument. In such case all of the resistors are removed as a unit, and a new set of resistors is placed in the casing. Also mounted in the casing 76 on the left-hand end thereof (Figure 3) is the cold junction resistor 14 that is placed in a separate box 14A (Figure 7) along with the cold junctions 30 and 35. The sheet metal casing 76 is pivoted at 79 on the frame portions 72A and 72B so that it may be swung up for inspection and cleaning of the slide wire 16 and collector 18 which are attached to the bottom thereof. The casing is maintained in its normal position by a spring plunger 80 which is mounted in the frame 72A and cooperates with a small indentation on the left face of the casing. The right-hand end of the casing receives a threaded shaft 81 having a milled head 81A which has a conical face on it. When the casing is in operative position the shaft 81 lies, as shown in Figure 5A, in a groove 82 in the frame portion 72B.

Attached to the bottom of the casing 76 is a plate member 83 made of some insulating material to which are fastened the slide wire 16 and the collector 18. These parts, as best shown in Figure 3, are not mounted on the member 83 so that they are parallel to its sides, but are mounted at a slight diagonal. This is done so that as the contact 29 moves along the slide wire and collector there will be a slight wiping action which will tend to clean the slide wire and at the same time will cause the contact to wear evenly rather than form a groove in its surface.

In originally calibrating the instrument it is desirable to be able to shift the slide wire relative to the contact carried by the print wheel carriage in order to adjust the zero of the instrument. To this end the insulating plate 83 is so mounted that it can be shifted endwise relative to the bottom of the casing 76. For this purpose the casing is provided with a tongue 84 that is punched upwardly from its bottom plate 85 as best shown in Figure 5. A screw 86 is rotatably mounted on the tongue 84 and has below the tongue a disk 87 to which is attached an eccentric pin 88. This pin extends into a groove 89 that is cut into the insulating plate 83 and extends across the latter. In order to adjust the plate which carries the slide wire relative to the casing 76, the screw 86 is rotated to move the pin 88. As the pin, which bears in the groove 89, is shifted lengthwise, the slide wire assembly will be moved relative to the casing 76. The entire slide wire assembly and the casing 76 are rigidly fastened in place on the frame 72B by the means of the screw 81. When for example, the casing 76 has been lifted upwardly around its pivots 79 for some purpose, such as cleaning the slide wire, it may be returned exactly to its original position by means of the screw 81. The conical head of the screw 81 cooperates with the groove 82 in the frame to pull the entire assembly tightly against the frame 72B to locate the same in some given position.

In order to shift the contact 20 along the slide wire 16 to rebalance the potentiometer in response to an unbalance thereof produced by a change in temperature of one of the thermocouples, the contact 20 is held in engagement with the slidewire and the collector bar and is mounted on a print wheel carriage 90. This print wheel carriage has extending from its upper rear face a clamp plate 91 in which the ends of the cable 60 are clamped. Therefore, as the motor 5 rotates, the print wheel carriage will be moved back and forth across the instrument and carry the contact 20 with it across the slide wire to a position of balance. This print wheel carriage has on it a print wheel 92 that is provided with printing characters or numerals 93 which are to be moved into engagement with the chart when the print wheel carriage reaches a balanced position. The manner in which the print wheel carriage operates will now be described.

Refer now to Figures 19 to 23 which show the print wheel carriage in detail. The print wheel carriage 90 is supported at its front end by a roller 94 that is received in a channel member 95 which runs the length of the instrument, and is attached at its ends to the frame members 72A and 72B. The rear end of the print wheel carriage is supported by means of rollers 96, 97, and 98 which bear against and roll on a shaft 99 that is also attached to the frame parts 72A and 72B at its ends. The rollers 96 and 97 are rigidly mounted on the print wheel carriage, and the roller 98 is supported on a spring 100 which is attached to the print wheel carriage. In this manner, the roller 98 is forced into engagement with the rod 99 to prevent any upward movement between the print wheel carriage and the shaft, and to keep the print wheel carriage rigidly mounted in position as it moves back and forth across the chart 219, upon which the recording of the temperature is to be made. The print wheel carriage 90 has formed on one side thereof, a downwardly extending plate 101 which has a stud shaft 102 rigidly mounted therein. Pivoted on this shaft is a supporting plate member 103 that has a roller 104 journaled on its rear end. This roller rides in a channel member 105 that is moved in a manner to be described later, for the purpose of producing the printing operation, and for the purpose of actuating a switch to connect the instrument to different thermocouples.

As more particularly shown in Figure 21, the shaft 102 has a sleeve 106 rotatably mounted on it. This sleeve, along with a second sleeve 108, that is rotatable on the first, is held in position on the shaft 102 by means of a suitable lock washer 107. The plate 103 is staked to the sleeve 106 so that the plate and sleeve can oscillate around the shaft. The sleeve 108 has a gear 109 and a ratchet wheel 110 staked to it. The ratchet wheel serves the purpose of rotating the sleeve 108 on the sleeve 106 to rotate the print wheel and an ink pad assembly which is mounted on the former sleeve. The ink pad assembly is made of a tubular moulding 111 that may be of plastic or metal and which is formed with a series of radially extending fins 111A that serve to divide this moulding into a series of compartments. The axial bore of the moulding has a circular flange with a sloping face or surface 112, formed on its right-hand side, which engages with a cooperating surface 113 on a flange member 114 that is suitably fastened to the sleeve 108. This member is provided with a pin 115 that cooperates with a groove 116 formed in a central open-

ing 117 in the flange of the moulding 111. The central opening 117 of the flange is eccentric in shape as shown best in Figure 22. The ink pad assembly is held on sleeve 108 by means of a knob 118 that has a cam face 119 engaging the left end of the moulding and which serves to properly center the assembly. Located within the radially extending compartments of the moulding 111 are felt pads 120, each of which may be impregnated with a different color ink if desired, so that each of the records made of the different thermocouple temperatures will be recorded in a distinctive color. The felt pads are held in place in the moulding by means of a shield 121 as best shown in Figure 21.

The ink pad assembly is mounted on the pen carriage by moving the moulding 111 containing the pads on the sleeve 108 from the left in Figure 21. Since the printing characters 93 normally engage the ink pads 120 some means must be provided for keeping these parts separated while the ink pads are being moved into place. This is the reason why the central opening 117 is made eccentric in shape. In mounting the moulding 111 on the sleeve 108, the moulding is first rotated until its groove 116 is lined up with pin 115, and moved toward the right in Figure 21. The moulding is then moved clockwise from the axial position in Figure 22 around pin 115 as a center (counter-clockwise in Figure 19) to separate the felts 120 and the printing characters 93. Thereafter the moulding is again moved to the right in Figure 21 until its surface 112 engages surface 113. Knob 118 is then screwed into place; engagement between its surface 119 forcing surfaces 112 and 113 into engagement with each other. Thus the moulding is rotated back into an axial position and centered by the concentric surfaces 113 and 119 with the ink pads 120 in engagement with the printing characters on the print wheel.

Also mounted on the plate 103 is a stud shaft 122. This shaft has rotating upon it, a sleeve 123 that is held in place by means of a washer 124. Staked to the sleeve is a drive gear 125. Also mounted on the sleeve 123 is the print wheel 92 that is held in proper position relative to the sleeve by means of engagement between a slot in the print wheel, and a pin 126 extending from the sleeve. Before the print wheel is placed on the sleeve, an indicating disc 127 is moved into place as shown best in Figure 23. This disc has a series of numbers on it which correspond to the print characters 93 on the print wheel, and are so displaced with respect to these characters, that when a printing character is in engagement with the chart, the corresponding numeral on this disc will be in a position where it can be seen from the front of the instrument as shown best in Figure 2. A pointer 128 is attached to the plate 103, and cooperates with the disc 127 to indicate the proper number. The print wheel and the indicating disc are held in place on the sleeve 123 by means of a knob 129 that is screwed on the outer end of the sleeve. As best shown in Figure 20, the gear 109 serves to drive the gear 125 by means of idler pinions 130, both of which are mounted for rotation on the plate 103.

Since it is imperative that the print wheel be exactly located with respect to the print wheel carriage a spring 131 is placed between the plate 101 of the print wheel carriage and the oscillating plate 103. This spring serves to take up any slack in the parts, and always keeps the plate 103 properly placed, with respect to the plate 101.

For a similar reason, a spring 132 is inserted between the plate 103 and the gear 125 in order that the print wheel will be properly located on its shaft 122.

The print wheel carriage 90 is also provided on its front end, with an indicating pointer 134 that cooperates with a scale 135, which is attached to the channel member 95 and extends across the front of the instrument. This indicator serves the purpose of showing the value of the temperature being measured as it is moved in front of the scale 135.

The print wheel and the ink pads are normally kept from rotating on their shafts by means of a pawl 136 that is pivoted at 137 on the plate 103, 15 and which is biased into engagement with teeth on the ratchet wheel 110 by means of a spring 138. A roller 139 which extends from the pawl 136 engages a surface 140 on a second pawl 141 that is pivoted at 142 on the plate 101. This pawl 141 is normally biased in a counter-clockwise direction in Figure 20, by means of a spring 143 that is equal in strength to the spring 138. This latter pawl is used to rotate the print wheel to bring a new printing character into printing position above the chart each time a new thermocouple is connected to the instrument. The operation takes place due to an oscillation of plate 103 which is imparted thereto by means of the channel member 105. This channel member is moved in an arc concentric with the stud shaft 102, by means of a mechanism to be described, after the instrument has reached a balanced position.

Cable 60 which is used for driving the print wheel carriage passes over four pulleys 145, 146, 147, and 148, and over the drive pulley 59 that is operated by the shaft of motor 5. This drive pulley will be described more in detail below. Pulley 145 is rotatably mounted on a stud 149 which projects upwardly from the arm 150. The arm 150 is pivoted at 151 and is biased by a spring 152 in a direction to take up all slack in the cable. The pulley 146 is rotatably mounted on a stud 153 which is carried by a boss that is formed in the frame 72, as best shown in Figure 8. The pulley 147 is rotatably mounted on a stud 154 which is mounted at its upper end in the frame 72 located at a point to the right of pulley 59 in Figure 8.

The pulley 148 over which the cable 60 also passes is attached to a bushing 148A that is journaled in a bearing 148B which is fastened to the frame 72A, as best shown in Figure 12A. The bearing is provided with a sleeve 148C which receives the bushing. As has been previously stated the instrument is provided with a detecting mechanism which operates to detect when the instrument comes into balance, and in response to such balanced position to operate a printing mechanism and connect the instrument to another thermocouple. It will be remembered that a detecting plate 61 is moved by the cable 60 to give an indication when the cable has stopped moving and the printing carriage is properly positioned. This is done by frictionally mounting the plate 61 on the bushing 148A. To this end the plate 61 is frictionally received between a flange 156 formed as part of the bushing 148A and a washer 157 which is rotatable with the bushing but may move axially thereof. Extending through the bushing is a bolt 155 which has between its head and the washer 157 a second washer 155A. The latter washer is drawn into engagement with the former by a spring 158 that

is compressed between the upper end of bushing 148A and a nut 155B. The amount of friction between the plate 61 and the parts 156 and 157 may be adjusted by varying the tension of the spring 158. A second nut is placed on the end of bolt 155 beyond nut 155B to lock the latter in place.

As the plate 61 is rotated along with the pulley 148 when the instrument is in its unbalanced condition, this plate is periodically brought back to a neutral position by a cam 159 which is driven at a constant speed by the motor 64, and which cam is mounted to rotate with its driving gear 159C on a hollow shaft 159D that is attached to and extends from the side of frame 72A (see Figure 18). The cam 159 is a three lobe cam and it has three high points 160 which periodically pass through a V-shaped groove 161 that is formed in the plate 61. One side of this groove is extended to form a tongue 162 on the end of the plate 61. The cam 159 is provided with three pawls 163 which are pivoted at 164. These pawls can move between the position shown in Figures 12 and 13, and the dotted line position of Figure 13 and are held in either position by engagement between the following end of the pawl and a spring 165 which is mounted on the cam. The movement of the pawls is limited by a pin 163 on each pawl which extends through an opening 194 in the cam. Each pawl is formed with a single projection 166 midway between its edges on its leading end, and with two projections 167 adjacent the edges of the pawl on its following end. The terms "leading" and "following" refer to the direction of travel of the pawl with the cam 159, the latter rotating in a clockwise direction in Figure 12.

In the operation of the instrument, the cam 159 is rotated at a constant speed. Assuming that the instrument is in an unbalanced position and that the print wheel carriage is being moved in one direction or the other, this means that the plate 61 will be rotated so that the edges of the slot will bear against one side or the other of the cam. This plate is periodically brought into a neutral position as a point 160 of the cam passes through the apex of the slot 161. If the instrument is still unbalanced, the plate 61 will have been moved either clockwise or counter-clockwise in Figure 18, so that the tongue 162 will be out of the path of the projection 166 and will be in the path of one of the projections 167 by the time the pawl reaches the tongue. This will continue until such time as the instrument reaches balance, when the plate 61 will remain in its neutral position after it has been moved there by the cam. The tongue 162 will then be in the path of the projection 166 on the next pawl 163 which moves past this tongue. Consequently the tongue will then engage the projection 166 and move the pawl clockwise in Figures 12 and 13 to the dotted line position of the latter figure.

When the pawl is moved in its clockwise direction a cut-out portion 168 of the pawl will be moved radially inward of the cam until it is in the path of a pin 169 that projects from one arm of the crank 170 attached to a shaft 171 journaled in the hollow shaft around 159D which the cam 159 rotates. Normally during the time that the instrument is unbalanced, the inner surface of the pawls are at a radially greater distance from the shaft 171 than the pin 169, but when the instrument reaches balance, the next pawl passing the plate 61 is flipped so that its

lower end moves inwardly to bring it into engagement with the pin 169. The crank 170 is thereupon rotated to perform the operation of printing and connecting the instrument to another thermocouple.

The outer end of the crank is provided with a roller 172 that moves in a slot 173 which is formed in the end of a lever 174. This lever is provided with a bushing 189 that rotates on a shaft 175 which is attached to and extends from the frame 72A. A second lever 176 is rotatable on the bushing 189, and has its outer end fastened to the channel member 105 to move the latter. It might be noted at this point that the other end of the channel 105 may well be fastened to a second lever, not shown, of the same length as lever 176 which second lever is pivoted at a point coaxial with the shaft 175 and on the frame 72B so that the two levers and the channel 105 will form a yoke that will move as a rigid member. The lever 176 is moved by the lever 174 to actuate the print mechanism by means of a spring 179 which has one end attached to each lever. The angular position between the two levers may be adjusted by means of an adjustment screw 177 which is fastened to an inwardly bent tongue 190 on the lever 174 and engages an abutment 178 on the lever 176.

The crank 170 is shown in Figure 12 at its rest position. When one of the pawls is flipped to a driving position and the crank is rotated, the first action of the latter is to move the levers 174 and 176 in a clockwise direction as the crank moves past point 180 in the cam slot. This movement serves to bring a printing character on the print wheel 92 into engagement with a chart passing over the chart drum 144. If the printing character engages the chart before the roller 172 has reached the point 180 of the cam slot the spring 179 will give to permit overtravel of the lever 174. Continued rotation of the crank will first move the lever 174 and the parts connected to it in a counter-clockwise direction and then in a clockwise direction until such time as the roller 172 again reaches the position shown in Figure 12.

As the crank 170 rotates, it will be subjected to varying loads depending on whether it is moving the lever 174 in one direction or the other. In order to smooth out the load on this crank, the shaft 171 is provided with a disc 191 (Figure 17) to which a cam 181 is adjustably attached by means of screws 192. This cam is engaged by a roller 182 that is mounted on the end of a lever 183. The lever 183 is pivoted at 184 and is biased to bring the roller 182 into engagement with the surface of the cam by a fairly stiff spring 185. As shown in Figure 17, the cam and roller are in relative positions that will be assumed when the crank 170 is at rest as shown in Figure 12. It will be noticed that the roller 182 is resting in a low spot 186 on the surface of the cam to definitely locate the crank 170 with respect to the cam slot 173. As the crank starts to rotate, cam 181 will be rotated about half-way to the high point 187 as roller 172 reaches point 180 of the slot 173. Thereafter, the cam surface continues to rise during the time that the lever 174 is being moved in a counter-clockwise direction. Such operation serves to put a load on spring 185 to retard the action of crank 170 and prevent it from running ahead of its driving pawl. When the crank has reached such a rotative position that it starts to move lever 174 clockwise in Figure 12, the cam 181 has reached a position where

its radius begins to decrease so that the force of spring 185 gives a slight camming action to the shaft 171 to help bring the crank 170 smoothly to its rest position.

By the time crank 170 has completed its revolution the instrument will have been connected to another thermocouple and will have begun to rebalance itself. If the instrument has not come to balance again the tongue 162 will engage one of the projections 167 of the driving pawl to move that pawl counter-clockwise on its pivot 164 and shift portion 168 radially outward beyond the pin 169. Crank 170 will then remain at rest until such time as the tongue 162 is centered and engages the projection 166 on another pawl. If, however, the instrument has rebalanced itself prior to the time crank 170 completes a revolution the tongue 162 will be centered and the driving pawl will not be moved out of driving engagement with pin 169. As a result the crank will continue its rotation and immediately proceed with another printing operation.

It is noted that a stop 188 is provided beneath the part 61 to back up this part, and prevent its being bent, if for some reason the cam should exert an unduly large force downwardly on this part.

The three lobe cam disclosed in Figure 12 makes an instrument that is practically instantaneous in printing after the instrument has come to balance. In some cases it may be desirable to have a slightly longer delay between the time that the instrument comes to balance and a printing operation takes place. In such a case a two-lobe cam as shown in Figure 15 at 159A or a single lobe cam as shown in Figure 16 at 159B may be used. It is also noted that the speed of rotation of the cam 159 may be changed to accomplish the same purpose. By designing the instrument with a cam with the proper number of lobes and the proper speed of rotation, almost any speed of operation can be obtained. Generally speaking, however, the speed of rotation of the cam is correlated with the speed and operating characteristics of the balancing motor 5.

It may be that the print wheel carriage has practically moved into printing position and can be moved the remainder of the distance between the time one of the points 160 of the cam 159 has centered member 61 and the time that projection 166 of the next pawl passes the tongue 162. If this is the case the tongue 162 will have moved slightly out of neutral, but not far enough to be in the path of a projection 167. A printing operation will therefore occur. It is possible for the instrument to be almost balanced, but not quite close enough for the above operation to take place. If this is the case tongue 162 may first engage projection 166 and then projection 167 to first throw the pawl into and then out of driving position before its cut out portion 168 has traveled far enough to engage pin 169. Moving the pawls forwardly or backwardly on the cam 159 relative to points 160, and varying the distance between projections 167 as well as the width of tongue 162 will have an effect on the amount of movement of the print wheel carriage that will be permitted after the member 61 has been moved to its neutral position. As an example, if the cam 159 is rotating at a speed of one revolution every three seconds, printing operations can occur at a minimum of once every three seconds. If a three lobe cam is used a printing operation will take place within a maximum time of one second after the instrument has balanced out and may

occur in a shorter time if the instrument is almost balanced when the member 61 is moved to its neutral position. The maximum time that will occur between any two printing operations is equal to the time it takes the print wheel carriage to move from its old to its new position plus one second. This time, therefore depends upon the speed of motor 5.

By using various combinations of cam speeds and pen carriage speeds almost any desired speed of operation of the recording mechanism may be obtained as shown by the table below. In the table the "cam speed" is in seconds per revolution; the "carriage speed" is in seconds for the print wheel carriage to move from one end to the other of its path of travel; and "% of chart" is the percent of full scale travel which can be covered by the print wheel carriage during the minimum time between two consecutive recording operations. For example, if a two lobe cam is used and is rotating at a speed of 6 seconds and the carriage has a speed of 11 seconds for full scale, a printing operation will occur every six seconds if the consecutive records are not more than 43% of the chart width apart. If the records are further than 43% of chart width apart, printing can occur after any three seconds after the instrument comes to balance. Again, if a three lobe cam having a speed of three seconds per revolution is used in an instrument having a carriage speed of 22 seconds, a printing operation will occur every three seconds if the consecutive records are not more than 7.5% of the chart width apart. If the records are further apart than 7.5% of chart the printing can occur within one second after the print wheel carriage is properly positioned.

Cam Lobe	Cam Speed	Carriage Speed	Percent of Chart
1	3	11	17
1	6	11	43
1	15	11	100
1	3	22	7.5

In the operation of the print wheel, as the channel 105 is moved upwardly, the member 103 will be moved in a counter-clockwise direction in Figure 19 or a clockwise direction in Figure 20 to bring a printing character 93 into engagement with a chart that is placed over a chart driving drum 144.

Due to the shape of the slot 173 in lever 174 the print wheel will be moved slowly into engagement with the chart with sufficient force to produce pressure printing, rather than hammer printing as is so often the case in multiple recording instruments. Pressing the printing character into engagement with the chart rather than drop-

ping it into engagement therewith produces quieter operation as well as being easier on the various parts. When the print character engages the chart the spring 179 will flex to permit lever 174 to move through its full stroke. Upon continued rotation of shaft 171 the lever 174, as has been described, will be moved downwardly in Figure 12. This means that the member 103 will be moved counter-clockwise in Figure 20 with the pawl 136 in engagement with ratchet 110 thus preventing any relative rotation of the parts mounted on member 103. As this movement continues the roller 139 on pawl 136 will move to the right along the surface 140 until such time as the lever arm between roller 139 and the pivot 142 for pawl 141 has been shortened enough for the force of spring 143 to overcome that of spring 138. At that time the pawl 141 will move into engagement with the ratchet 110 and, acting through the arm 140, will move pawl 136 out of engagement with the ratchet. This will occur at the bottom of the stroke of lever 174, and with the printing wheel in its highest position above the chart drum. Continued rotation of the crank 170 will then begin to move the lever 174 clockwise in Figure 12, which means that member 103 will move clockwise in Figure 20. During this movement the pawl 141 is in engagement with the ratchet 110 and will thereby prevent that ratchet and the gear 109 from rotating relative to the part 101. While the member 103 is moved clockwise, however, idlers 130 and gear 125 upon which the print wheel is mounted will rotate, thereby moving the print wheel clockwise in Figure 20 and counter-clockwise in Figure 19 to bring a new printing character into printing position above the chart drum. As this clockwise movement of the part 103 continues the roller 139 will move away from the pivot point 142 and the lever arm between 139 and 142 will become large enough for spring 138 to overcome the force of spring 143. At this time the pawl 136 will move into engagement with the ratchet 110 and maintain the parts in the position shown until the next printing operation occurs. It will be seen, therefore, that the ratchet is positively locked for movement with the part 103 by pawl 136 or is positively locked against movement by the pawl 141. At no time is the ratchet wheel, and therefore the print wheel, free to rotate because the pawls are so designed that pawl 141 is moved into engagement with a tooth of the ratchet as pawl 136 is moving out of engagement therewith. It will, therefore, be seen that as the crank 170 starts to rotate after the instrument has come into balance its movement will produce a printing operation and then an operation whereby a new printing character is brought into printing position above the chart.

The same movement of the channel member 105 that brings the print wheel into engagement with the chart and rotates the print wheel also serves to connect another thermocouple to the instrument. This is done by rotating brushes in a switch into engagement with other contacts of the switch. A switch by means of which this may be accomplished is shown at 165 (Figure 8) in the drawings and may well be of the type described and claimed in Harrison Patent 1,770,918, issued April 22, 1930. Such a switch is provided with a shaft 196 by means of which the brushes may be rotated. As shown herein, the switch is mounted on a bracket 197 that is attached to a portion of the frame 72A.

The movement of the channel member 105 acts to rotate the shaft 196 by means of a connector 198 (see Figure 17) which is attached to the channel member near one end and which is pivoted to one end of a pivoting link 199, the other end of which is pivoted to one arm of a lever 200. This latter lever is mounted for rotation around a shaft 201 and has mounted on its other arm a pawl 202 that is pivoted at 203 on the lever. Pawl 202 is biased by means of a spring 204 in a direction which will bring its end into engagement with one or the other of the teeth of a ratchet 205. Movement of the lever 200 is used to rotate the ratchet and a bevel gear 206 that is attached thereto, both of them being mounted on the shaft 201. The pawl 202 is provided with a roller 207 that is adapted to move along a surface 208 formed on one arm of another pawl 209 that is pivoted at 210 on a plate 211. This plate forms part of a bracket 212 that serves to support the switch actuating mechanism and the shaft 201. Pawl 209 is biased in a counter-clockwise direction by spring 213 which is equal in strength to the spring 204. Beveled gear 206 meshes with a beveled pinion 214 that is attached to the upper end of a shaft 215 which serves to rotate the switch shaft 196. Shafts 215 and 196 are joined together by means of a universal joint which, in this case, comprises a spring metal plate 216 that is fastened to the shaft 215 at diametrically opposed points 217 and is fastened to the shaft 196 at point 218. The universal joint serves to compensate for any slight misalignment that may appear between shafts 215 and 196.

On the initial upward movement of the channel member 105 when a printing operation takes place, the pawl 202 will move the ratchet 205 a slight amount in a clockwise direction. This movement is imparted thereto through link 199 and lever 200, and has no effect on the switch except to move its brushes slightly backwards on the contacts. When, however, the channel member 105 starts its downward movement in Figure 17, the lever 200 is moved in a counter-clockwise direction and acts through the pawl 202 to rotate the ratchet 205 also in a counter-clockwise direction. This movement is imparted to the gearing and through shaft 215 to switch 195 to connect another thermocouple into the potentiometer circuit, the arrangement being such that the connection is made immediately after the downward movement begins. It will be seen that immediately after the printing operation takes place the switch is adjusted to connect another thermocouple to the instrument. After this operation is performed, the upward movement of the channel 105 is used to reset the pawl and ratchet mechanism of the pen carriage, and the switch adjusting mechanism. While this adjusting movement is taking place, the potentiometer is being rebalanced so that no unnecessary time is lost between printing operations. The ratchet mechanism used for adjusting the switch is similar in operation to that previously described which was used on the print wheel carriage. As the lever 200 moves counter-clockwise, roller 207 will move toward the pivot 210 until such time as the leverage between the two pawls changes enough for the force of spring 213 to overcome that of spring 204. When this occurs, pawl 202 will be lifted out of engagement with the ratchet, and pawl 209 will move into engagement with the same. This occurs near the bottom of the stroke of lever 200. Thereafter, as lever 200 moves in a clockwise direction, the ratchet wheel

will be held from turning by pawl 209 as pawl 202 is moved to a position in which it can engage the next tooth on the ratchet wheel.

The chart, which has been mentioned above, is shown best at 219 in Figure 2. It will be seen that the chart is provided with horizontal and vertical lines, and has on one edge a series of round holes 220, and on its opposite edge a series of slots 221. The horizontal lines on the chart serve the purpose of indicating the time at which some particular record is made, while the vertical lines or calibration marks serve to indicate the value of the temperature that has been recorded. As best seen in Figure 12, the supply roll 222 of the chart is mounted between the frame portions 72A and 72B near the bottom, and toward the rear of the frame. The chart, when being inserted into the instrument is pulled upwardly, and forwardly over the rod 223. The chart is then threaded toward the rear of the instrument between a guide member 224, and the chart drum 144. This guide member serves to direct the chart around the drum, from which it is brought down across the front of the instrument, and over a chart backing plate 225 to a chart take up roll 226, which is located at the bottom of the frame directly in front of the supply roll.

The backing plate 225 is preferably hinged at 30 its lower end, as shown at 227, so that it may be moved out of the way when a new chart is to be inserted into the instrument. The backing plate is held in place by means of a pair of lock members 228 that engage cut-out portions 229 on the upper corners of the backing plate.

These locking members are held in engagement with the portions 229 of the backing plate by means of spring members 230 upon which they are mounted.

40 The supply roll 222 and the take-up roll 226 are mounted at their left ends in Figure 2, or their right ends in Figure 8 in the frame portion 72A, upon a spring mounted chuck 231 shown in Figure 10 which is adapted to be wedged into 45 the end of the core 232 of a supply or take-up roll. This chuck is attached to a shaft 233 that is mounted for rotation in a bushing 234 inserted in the frame 72A. The chuck is forced to the left in Figure 10 into engagement with the end 50 of the roll by means of a spring 235, and is limited in its movement by a washer 236 on the outer end of the shaft. It will be noted that the shaft 233 is made of a large diameter near the chuck and a small diameter to the right thereof. 55 This construction gives a large and rigid bearing surface near the end of the chart roll and permits the use of a bushing 234 of the type shown which fully encloses the spring 235.

The left end of the supply roll 222 in Figure 8 60 or the end in frame portion 72B is mounted on a non-rotatable chuck 292, shown in Figure 11, that is attached to a shaft 293 which is threaded through the frame 72B. This shaft may be provided with a knob 294 to rotate it and shift the 65 chuck axially. In any event a lock nut 295 is threaded over the shaft and is jammed against the frame to hold the chuck firmly in position when it has been adjusted. Since the chuck 292 is non-rotatable it serves to put a drag on the supply roll to prevent the same from over-running. Both the chuck which supports the left end of the supply roll and that which supports the left end of the take-up roll, to be described below, are axially adjustable so that the rolls 70 75 may be shifted to the proper position relative to

the chart drum 144. The right end of the take-up roll 226 adjacent frame portion 72B is supported by an adjustable and rotatable chuck 237 shown in detail in Figure 8. The chuck is provided with a tongue 238 that is adapted to engage the usual driving notch formed in the end of the roll core (see Figure 2). This tongue extends through an opening in the edge of the chuck and is formed of spring material which always acts to move out into the position shown. When inserting a roll over a chuck of this type, the tongue 238 will be moved against the flange of the chuck. Thereafter, as the roll or the chuck is rotated, the tongue will spring into its driving position as soon as the driving notch of the core is in alignment therewith. The chuck 237 is attached to a shaft 239 whose outer end is provided with a knob 240 whereby the chuck can be rotated at will to supply or take up slack in the chart. The shaft 239 is journaled in a sleeve 241 that is threaded through an opening in the frame 72B. The outer end of this sleeve is provided with a thumb nut 242 whereby the sleeve can be rotated in order to shift the chuck to its proper axial position and is provided with a lock nut 243 that can be jammed against the side of the frame to hold the sleeve in place.

The chuck used for the take-up roll has attached to the shaft 239 a sprocket 244. This sprocket is driven by a chain 245 that extends over a second and larger sprocket 246. An idler sprocket may be used against the chain to take up slack if this is deemed necessary. In order to compensate for increasing diameter of the chart on the take-up drum the sprocket 246 is frictionally driven by the chart drum 144 by means of a pair of friction washers 247 that are keyed to a shaft 248 on the end of the chart drum. The sprocket and the friction washers are moved together and against a nut 249 that is screwed on the shaft by means of a plate 250 which is forced to the left by springs 252. Each of the springs 252 surrounds a plunger 251 which is attached to the plate 250 and which is freely movable through openings that are formed in the end of the chart drum. In order to adjust the tension of the springs, and therefore the friction with which the sprocket 246 is driven, the nut 249 may be moved to the left or right along the shaft 248.

The chart drum in this embodiment of the invention is driven at a constant speed by the motor 64 through a gear train 253 that starts with the pinion 64A (Figures 12 and 18) and ends with the gear 254 that is frictionally mounted on the drum. It will be seen from Figure 2 that the chart drum is provided on each end with a series of projections 255 that project through the openings 220 and 221 in the chart. By means of these projections and openings the chart is positively moved past the print wheel at some given speed. The speed of the chart drum may of course be changed by substituting a different gear reduction between the motor and the chart drum. The shaft 248 upon which the chart drum is mounted is provided with a knob 256 by means of which the chart drum may be rotated to properly position the chart with respect to the print wheel. There is also provided a member 296 which extends over the edge of the chart and which can be used as a guide to properly set the time lines on the chart relative to the print wheel and a so-called tear-off strip 257 which is made of some transparent material and which extends across

the instrument in front of the chart. The purpose of this member is to act as a straight edge when a piece of the chart is to be removed.

The drive motor 5 which serves to move the print wheel carriage back and forth across the chart is mounted beneath the chart and behind the broken portion of the frame as shown in dotted lines in Figure 8 and in Figure 9. This motor has extending therefrom a shaft upon which is mounted a pinion 258 that meshes with and drives the gear 58 to which is attached the pulley 59 around which cable 60 is wrapped. The gear 58 is made with teeth around most of its periphery and is provided with a projection 259 either side of which can jam against the pinion 258 to limit rotation of the gear and therefore travel of the print wheel carriage. Gear 58 and pulley 59 are attached by rivets or other suitable means to a sleeve 260 that is rotatable on a shaft 261 which is suitably attached to and projects from the rear of frame 72. Roller bearings 291 are provided between the sleeve 260 and shaft 261, and the sleeve is held on the shaft by a bolt 298 which is prevented from rotating relative to the shaft by a set-screw 299. If it is desired the cable 60 may be attached to the pulley 59 by any suitable means to prevent the possibility of any slippage occurring between the two.

The instrument is also disclosed as being provided with a switch S, shown in Figure 8, that can be used to actuate a signal when some predetermined temperature occurs, or for any desired control purpose. The switch S herein is operated by a cam 262 that is mounted on the sleeve 260, and held in proper position thereon by spacer members 300 and a thumb nut 301. The cam has a cut out portion 263 that is joined with the surface of the cam by inclined edges 264 and 265. The switch itself is mounted on a plate 266 that is suitably attached to the frame 72. Attached to the plate 266 and insulated therefrom is a piece of material 267 upon which the switch blades are mounted. One blade is shown at 268, and has a contact 269 on its right end. The second blade is numbered 270 and is shown as being pivoted to the member 267 at 271. This blade has a contact 272 on its right end which is adapted to engage with the contact 269 and is normally held in engagement with this contact by means of a spring 273. Also mounted for rotation around point 271 is a lever 274 which has a roller 275 projecting from it into engagement with the surface of the cam 262.

In the operation of the instrument, it may be assumed that the gear 58 and cam 262 are rotating in a clockwise direction in Figure 8. From the position shown in that figure, the rotation of the cam 262 will move the cut-out portion 263 to the right, and cause roller 275 to ride up inclined surface 264 to an idling position on the surface of cam 262 with the contacts 269 and 272 closed. Thereafter upon a reverse movement of the cam 262, or a movement in a counter-clockwise direction, the roller 275 will bear on the edge 65 of cam 262 until first the inclined surface 264 and then the cut-out portion 263 comes under the roller, at which time it will return to the position shown in the drawing. Continued rotation of the cam will move the roller 275 up the surface 265 again to the edge of the cam. As this is taking place, the left side of lever 274 will move into engagement with the left end of switch blade 270, and thereby move that blade around its pivot and against the force of spring 273 to separate the switch contacts. Continued rotation of the cam

after this occurs will not have any effect on the switch and will merely hold the roller 275 in position with the switch contacts apart. The cam 282 may be adjusted relative to the gear 58 by loosening the thumb nut 301 and by rotating the cam on the sleeve 269. This adjustment is preferably made with the pen carriage in the position at which the switch is to be actuated. The cam is then moved on sleeve 269 until the switch is just opened or closed as the case may be, and the thumb nut 301 is then tightened.

It was pointed out above in the description of the wiring diagram that the standardizing switch 21 could be moved to bring contacts 25 and 37 and contacts 28 and 38 into engagement with each other in order to standardize the instrument. The manner in which this is accomplished is shown in Figure 12. Mounted with the switch and above the same is a spring leaf 278 that is engaged and moved by an adjustable screw 279 which is in turn mounted on a lever 280. In order to move the switch to its standardizing position, the lever 280, which is pivoted at 281, is moved in a counter-clockwise direction to bring the leaf 278 into engagement with button 24 by means of engagement between a pin 282 that projects from the lever 280 and a cam surface 283 that is formed on a shaft 284. This shaft is journaled for axial and rotative movement in the frame 72A in suitable bearings. The shaft may be rotated and moved axially by means of a knob 285 on its front end. In standardizing the instrument, the knob 285 is moved to the left in Figure 12 to move the operating knob 24 of switch 21 downwardly. Continued movement of the knob 285 will bring a clutch plate 287 on the left end of the shaft 284 into engagement with a second clutch plate 289 on the shaft 290 of the standardizing rheostat 10, 11 which has been described. After the clutch plates have been connected and the switch has been thrown, rotation of knob 285 will adjust the resistances 10 and 11 to standardize the instrument. It is noted that contacts 12 and 13 are insulated from the frame 72A by means of a bracket 291 that is attached to the frame.

In the embodiment of the invention that has been described above, there was disclosed a continuous chart drive. In some applications, it may be of advantage to have a chart which is driven intermittently, or in step by step fashion. Such construction is disclosed in Figures 24 and 25. The driving force which is used in the intermittent chart drive consists of a two lobe cam 305 which is driven through suitable gearing 306 that derives its power from the pinion 64A on the shaft of motor 64. Through suitable mechanism later described, the cam rotates a shaft 307 that is journaled in a bearing attached to the inside of frame 72A, which shaft has a worm 308 on its right end that engages with a worm wheel 309 attached to the shaft of chart drum 144. The shaft 307 is rotated by means of a ratchet 310 that is attached to the shaft and which is moved in a counter-clockwise direction in Figure 25, by means of pawl 311 that is biased in a counter-clockwise direction by means of a weight 311A. This pawl is pivoted at 312 on a plate 313 that is mounted to oscillate around the shaft 307. Plate 313 is moved in a counter-clockwise direction by means of engagement of a roller 314 on it, and the cam 305, against the tension of a spring 315 which tends to move the plate and pawl in a clockwise direction. The ratchet 310 is held against retrograde movement by means of a pawl 316 which is pivoted at 317 on an exten-

sion 318 which is formed as part of the bearing for shaft 307. In order to limit the clockwise movement of plate 313, and therefore the amount of rotation of shaft 307, for each rotation of the cam 305 there is provided a limit cam 320 that is engaged by pin 319 on the lower end of the plate 313 as the latter moves in a clockwise direction. This cam is attached to a shaft 321 that is rotatably mounted in projections 322 and 323 which extend from the left face of the frame 72A, bearing 322 being shown in Figure 25.

In the operation of this drive, the cam 305 rotates to oscillate plate 313 around the shaft 307. As the plate moves in a counter-clockwise direction in Figure 25, pawl 311 will rotate ratchet 310, and through the gearing drive the chart drum. As the low portion of the cam 305 comes over roller 314, the plate 313 will be moved in a clockwise direction by spring 315 to an extent depending upon engagement between pin 319 and cam 320. As the plate turns in its clockwise direction, the shaft 307 is prevented from rotating reversely by means of the pawl 316.

In order to adjust the cam 320 to different angular positions, and thereby adjust the speed of the chart drive, shaft 321 upon which the cam is mounted has also attached to it a plate 324 which is provided with a series of notches 325 that are adapted to be engaged by pin 326 which projects to the left from bearing 323, as shown best in Figure 24. The shaft 321 is mounted for axial movement, and is biased by means of a spring 327 in a direction to maintain the pin 326 in one of the notches 325. The shaft 321 can be moved to the left in Figure 24 to separate the pin from the notches in order to rotate the cam 320 by means of a knob 328 which is attached to the front end of shaft 321, and is accessible from the front of the instrument. This knob is provided with a pointer 329 which cooperates with a scale 330 attached to the frame. The scale may be calibrated in chart speeds such, for example, as inches per hour, or any other desired rate.

In some cases it may be desirable to have an instrument which is more sensitive than one which can be obtained with a slide wire of the length of the instrument, as shown, for example, in Figure 3. When this is done, a longer slide wire is necessary, the instrument being more sensitive since there is a smaller potential drop per unit length of the slide wire. In such a case it is desirable to have the slide wire wound in a helical form as shown in Figures 26 to 30 inclusive. In using a slide wire of this type, an assembly of the type shown at 331 is used. In this assembly the contact will be moved relative to the slide wire by means of a pulley assembly 332 that is fastened to the upper end of a shaft 333. In the instrument described this pulley assembly and shaft would take the place of pulley 146, and shaft 153 around which the drive cable is guided, as best shown in Figures 3 and 8. The slide wire assembly 331 will consist preferably of a support 334 which can be fastened in any suitable fashion to the frame 72, and will generally lie below the pulley 146 in a position occupied by the cut-out portion in the left-hand side of Figure 8. Attached to the support 334 is a tubular shaft 335 that along with a plate 337, acts to hold a ceramic core 336. This plate engages an internal shoulder in the core and an external shoulder on the tubular shaft, and is held in place by means of a nut 338, as best shown in Figure 28. In order to prevent rotation of the ceramic core with respect to the support 334, the latter is provided with a

downwardly extending pin 339 that engages a slot cut in the upper surface of the core. The outer surface of the core is formed with a pair of parallel helically disposed grooves in which the slide wire 16 and the collector 18 are placed. The ends of the slide wire and the collector extend through openings in the core and are brought up through the center of the same as shown at 340 to a terminal member 341 that is located on the top of the support 334.

In this case a contact 342, which takes the form of a small roller, is so placed that it lies between the slide wire and the collector, and is moved around the core in a helical path corresponding to that of the slide wire. This contact is mounted in a slot 343 which is formed in a spring holder 344. As the holder is rotated, the contact will move around the surface of the core in engagement with the slide wire and collector, and will move down and up in the slot as it follows the slide wire from the top to the bottom of the core and up again. In order to rotate the contact, there is provided a shaft 345 which is journaled in and extends through the tubular shaft 335. The shaft 345 has attached to it a radially extending arm 346, and rotatable upon it a second arm 347 which is bent upwardly as shown in Figure 28, and which supports the contact holder 344. This holder is attached to the upwardly extending portion of arm 347 by any suitable means which may be used to insulate the holder from the arm. The arm 347 may be adjusted relative to the arm 346 for calibration and adjustment purposes by means of an eccentric pin 348 which is rotatably attached to the arm 347, and extends through a slot in the arm 346. The two arms are fastened together by means of a clamp screw 349 which extends through an arcuate slot in the arm 346, and is screwed into the arm 347.

In order to drive the shaft 345 from the shaft 333, there is provided a clutch which consists of a plate 350 attached to the upper end of shaft 345, which plate has a pin 351 extending upwardly therefrom. This pin is received by notch 352 that is formed in the edge of a plate 353 which is attached to the lower end of shaft 333. This connection makes it easy to remove the slide-wire from the instrument for cleaning purposes, and also makes it easy to rapidly connect the two shafts in driving relation when the slide-wire is again replaced in the instrument. The entire slide wire assembly is protected by means of a cover 354 which can take the shape of a cup, and be moved upwardly into place, as shown in Figure 28 to completely surround and protect the assembly. This cover is held in place by means of spring members 355 which are pivotally attached in suitable openings on the support 334, and which extend around the lower end of the cover 354. The cover may be filled with oil to further protect the slide wire if necessary or desirable.

When a slide wire of this type is used, it has been found advisable to attach the ends of the drive cable to the pulley assembly 332 instead of the print wheel carriage as was done with the straight slide wire. In this case, the print wheel carriage would be clamped to an intermediate portion of the drive cable. To this end, the pulley assembly consists of a lower piece 356 which is fastened to the shaft 333.

This piece is provided with an opening 357 through which one end of the cable is passed, and to which it may be fastened. This piece also has on its surface a helical groove around which the ends of the cable may be wrapped a few turns.

The upper part of the pulley assembly consists of a member 359 that is also provided with an opening 360 in which the other end of the cable may be inserted and attached. This part 359 is attached to the lower part 356 by means of a suitable clamp screw 361.

In assembling the drive cable with the pulley in this embodiment of the invention, one end of the cable is first placed in the opening 357, 10 and a few turns wrapped around the groove 358. The cable is then passed around the remaining pulleys in a manner described in connection with Figure 3, and the other end of the cable is then wrapped for a few turns in the groove 353, and 15 has its ends passed through the opening 360, and attached to the upper part of the assembly 359. The screw 361 is then loosened, and part 359 is rotated relative to part 356 until the cable has been tightened sufficiently. The screw 361 is 20 then used to clamp the parts 356 and 359 together.

In order to synchronize the pen travel with the length of the slide-wire, it may be necessary to change the diameter of the pulley 356 so that a 25 given number of rotations of this pulley will exactly move the pen carriage through its full range of travel. This is accomplished by providing member 356 with two eccentrically located openings 352 that are joined by a cut 363 which 30 cut is in turn joined with the periphery of the member 356 by a second cut 364. This in effect makes an expansible pulley. The cut 364 has formed in it a conical opening 365, as best shown in Figure 29. A conical block 366 is placed in this 35 opening, and is held therein by means of a screw 367. In order to change the diameter of the pulley the screw is used to pull the block 366 up into the opening 365, and thereby make the cut 364 wider. This spreads the parts of the pulley 40 to make its diameter larger. In this fashion, the print wheel carriage will be moved a greater distance for each rotation of the pulley assembly. It will be seen from the above that the instrument will operate in exactly the same manner that was 45 described in connection with the straight slide wire. The only difference is that with a longer slide wire a more accurate positioning of the contact, and therefore of the pen along the chart, will then be obtained than was possible with the straight slide wire. Generally speaking, an instrument having a helical slide wire cannot be 50 operated as fast as one having a straight slide wire. That is, the pen carriage cannot be moved across the chart as quickly when a helical slide wire is used as it can when the contacts are connected to the pen carriage and are in direct engagement with the slide wire. The main reason for this is that a nice balance has to be obtained 55 between the force necessary in order to get good electrical contact between the contact 343, and the slide wire, and the centrifugal force that is produced as the contact supporting member 344 is rotated around the slide wire support. It will therefore be seen that the choice between the helical slide wire and the straight slide wire lies 60 in which is more important, increased speed or increased sensitivity.

Another form of drive crank for the printing mechanism is disclosed in Figures 31 and 32. 70 This form of crank consists of two parts which are moveable relative to each other, and which may be moved relative to each other in certain conditions to prevent a jamming action of the parts, and thereby the stalling of the motor 64. This drive crank consists of a driven disc 370,

corresponding to crank 170 in Figure 12, to which cam roller 172 is attached, and which is in turn mounted on the shaft 171 and prevented from turning relative thereto by means of a key 371 which is received by a collar 372, that is attached to the shaft. The second, or driving disc 373 is provided with an enlarged opening 374 that surrounds the collar 372, and is pivoted to the driven disc 370 at 375. The disc 370 is provided with an opening 376 that serves to give a clearance for the head of drive pin 169 that is riveted to the drive disc 373. Driven disc 370 is also provided with a slot 377 that receives a limit pin 378 which is riveted to the disc 373. Cooperation between this pin and the slot 377 limits the amount of relative movement which can be obtained between the discs 370 and 373. Each of the discs is provided with a pair of projections 379 which extend inwardly from the ends of registering slots formed in these discs. The projections overlap each other, and are both in the same plane as shown in Figure 31. The ends of the four projections 379 are received by a spring 380 which normally serves to keep the two discs in the relative position shown.

In the operation of the instrument with a crank of this type, one of the driving pawls 163, when it is moved to its driving position will engage the pin 169 and act through the disc 373 and the pivot point 375 to rotate the driven disc 370 to actuate the printing mechanism in the manner above described.

If the instrument has been stopped in such a position that the drive pin 169 is horizontal and in a direct line with the detecting member 61, there is a remote possibility that a pawl 163 might jam between these two parts and prevent rotation of the crank. If such an occurrence should take place, the pin 169 and plate 373 would be rotated counter-clockwise in Figure 31 relative to the plate 370, and against the force of spring 380. In this fashion driving pin 169 will move to the left and will permit the driving pawl 163 to slip past it. The next driving pawl will pick up this pin to complete the printing operation in the usual manner. Such a jamming action between the pawl is very unlikely to occur in view of the fact that the crank normally stops with the pin 169 below the horizontal position as shown in Figures 12 and 31, but this construction will take care of the possible contingency that the instrument is stopped with the pin 169 in a horizontal position where the jamming action might occur.

From the above detailed description it will be seen that I have made a rugged and positive acting potentiometer which will quickly and accurately move the recording mechanism across the chart to a position corresponding to the value of the condition being measured. The mechanism will then act to substantially immediately make a record of the condition value, and will start to move to a new position.

While in accordance with the provisions of the statutes, I have illustrated and described the best form of this invention now known to me, it will be apparent to those skilled in the art that changes may be made in the form of the apparatus disclosed without departing from the spirit of this invention as set forth in the appended claims, and that in some cases certain features of this invention may sometimes be used to advantage without a corresponding use of other features.

Having now described this invention, what I

claim as new and desire to secure by Letters Patent is:

1. In a self-balancing measuring instrument having a normally balanced circuit adapted to be unbalanced, the combination of a detector mechanism comprising a member moving in response to unbalance of said circuit, continuously operating means periodically returning said member to an undeflected position upon deflection thereof, a part carried by said means and engaged by said member to be moved into a first or second definite position depending upon whether said member is in its undeflected position or in a position to one side thereof, and mechanism driven by said part in one position of the latter.
2. In a self-balancing measuring instrument having a normally balanced circuit adapted to be unbalanced, means for detecting a balanced condition of said circuit comprising a member deflecting on either side of a neutral position depending upon the direction of unbalance of said circuit, a constantly rotating element operative to periodically return said member to its neutral position, a part carried by said element and having two positions, means to hold said part in either one of said positions, said member including a portion to engage said part and move it into one or the other of said positions depending upon whether said member remains in neutral position or not after it has been returned to that position, and mechanism operated by said part in one position thereof.
3. In a self-balancing measuring instrument having a normally balanced circuit adapted to be unbalanced, a detecting member movable to either side of a neutral position in response to unbalance of said circuit, a constantly rotating cam operable to periodically return said member to its neutral position upon deflection thereof, a pawl pivoted to said cam and adapted to move into one of two positions, said member having a portion lying in the path of said pawl to engage said pawl and move it to one position when said member is deflected and to engage said pawl and move it into its other position when said member is in its neutral position, and mechanism operated by said pawl when the latter is in said other position.
4. In a self-balancing measuring instrument having a normally balanced circuit adapted to be unbalanced, means to detect balance thereof comprising a member movable to either side of a neutral position in response to unbalance of the circuit, said member being formed with a V-shaped notch and an extension on one side thereof, a constantly rotating cam having a portion acting in said notch to periodically return said member to neutral position, a pawl pivoted to said cam at a point following said portion thereof, said pawl having a pair of projections to engage said extension and be moved to one position if said member has moved out of its neutral position, said pawl having a third projection to engage said extension and be moved to a second position if said member remains in its neutral position, and mechanism operated by said pawl in its second position.
5. In a self-balancing measuring instrument, means to record the value of a condition being measured, and means to detect balance of said instrument and operate said recording means comprising a member frictionally movable from a neutral position by said recording means as the latter is moved to recording position, a constantly rotating cam cooperating with said member to periodically return the same to a neutral position,

drive means carried by said cam and having portions cooperating with said member to be moved to an operative or inoperative position depending upon whether said member remains in its neutral position or is moved therefrom, and means operated by said drive means when the latter is in operative position to actuate said recording means.

6. In a self-balancing measuring instrument, recording means to make a record of the value of a condition being measured, means to shift said recording means to a position corresponding to the value of the condition being measured, a member frictionally driven by said shifting means to a position on either side of a neutral position, cam means operative to periodically return said member to its neutral position as it is moved therefrom by said shifting means, a drive pawl carried by said cam, means forming part of said member and lying in the path of said pawl to move said pawl to operative or inoperative position depending upon whether said member is in its neutral position or a position to one side thereof as said pawl passes said member, and means driven by said pawl when the latter is in its operative position to cause said recording member to make a record of the value of the condition.

7. In a recording instrument, a recording mechanism movable from a non-recording position to a recording position, means to shift said mechanism through a path to a point corresponding to the value of a condition, a deflecting member frictionally connected to move with said mechanism to either side of a neutral position depending upon the direction of movement of said mechanism in its path, a constantly rotating cam adapted to periodically return said member to its neutral position, a driving part carried by said cam and movable into either operative or inoperative positions, means to hold said driving part in either position, a projection on said member lying in the path of movement of said part and cooperating with the same to move said part into its operative or inoperative position depending upon whether said member is in its neutral position or to one side thereof, a crank mounted coaxially with said cam and having a portion thereof in the path of movement of said part when in its operative position, and means driven by said crank to move said recording mechanism from its non-recording position to its recording position and back again.

8. In a recording instrument, recording mechanism movable from a recording position to a non-recording position, means to shift said mechanism through a path to a point therein corresponding to the value of a condition, a member movable therewith from a neutral position to a position on either side of neutral as said mechanism is shifted, rotating means operable to periodically return said member to a neutral position, means to move said mechanism from non-recording position to recording position and back again, drive means for said moving means carried by said rotating means and normally in a position inoperative to act on said moving means, a portion of said member lying in the path of said rotating means and operative when said member is in a neutral position to move said drive means to operative position, whereby said moving means will move said mechanism to recording position.

9. In a measuring instrument, the combination of printing mechanism, a pivoted lever to

operate said mechanism upon oscillation of the lever, a rotatable crank operative to oscillate said lever, a shaft upon which said crank is mounted, means to rotate said crank at intervals, a cam on said shaft, and force applying means bearing on the surface of said cam to retard rotation of the cam as the radius of the cam increases with respect to the point of application of said force applying means and to help rotation of the cam as the radius of the cam decreases with respect to the point of application of said force applying means.

10. In a measuring instrument, the combination of recording mechanism, an oscillating lever to actuate said recording mechanism, said lever having a cam slot therein, a rotatable crank having a portion engaging said slot and operative to oscillate said lever upon rotation thereof, a rotatable shaft upon which said crank is mounted, means to rotate said crank at intervals to operate said recording mechanism, and means acting on said shaft to act against said rotating means during a portion of the rotation thereof and to act with said rotating means during the remainder of the rotation thereof.

11. In a multiple recording instrument a recording mechanism, means to move said mechanism to various positions depending upon the value of a condition, a member frictionally rotated by said mechanism, as the latter moves, to a position on either side of a neutral position, a constantly rotating multiple lobed cam cooperating with said member to return the same to its neutral position each time a cam lobe passes said member, a plurality of driving means movable into and out of driving position carried by said cam, cooperating means between said member and each driving means to move the latter into driving position if said member remains in its neutral position after having been returned there by one of the lobes of said cam, and means to operate said recording mechanism by said driving means.

12. In a multiple recording instrument, a recording mechanism, means to move said mechanism through a path to a position depending upon the value of a condition, a member moved around an axis by said mechanism, as the latter moves, to either side of a neutral position, a rotating cam having a plurality of lobes cooperating with said member to return the same to neutral position each time one of the lobes moves past said member, a driving means mounted on said cam in a position to follow each lobe as the cam rotates, said driving means each including parts cooperating with a portion of said member to be moved by said member into or out of an operative position depending upon whether said member has or has not remained in its neutral position, and driven means operated by said driving means when the latter is in operative position to actuate said recording mechanism to make a record of the value of the condition being measured.

13. In a self-balancing measuring instrument, a contact, means including a pen carriage to support and move said contact through a path to various positions depending upon the value of a condition being measured, a slide wire, means to mount said slide-wire in a position in which it may be engaged by said contact throughout the path of travel of the latter, and means to shift said slide wire relative to said contact including a stationary part, a member having an eccentrically located pin rotatable in said part, said

mounting means having a depression therein adapted to receive said pin whereby rotation of said member will shift said pin and thereby said supporting means.

14. In a self-balancing measuring instrument the combination of a potentiometer circuit including a slide wire and a contact to be moved along said slide wire to a position in which said potentiometer circuit is balanced, means to move said contact to balanced position including a recording carriage upon which said contact is mounted, means to support said slide wire in a position in which it may be engaged by said contact throughout the travel of the latter, and means to shift said support and slide wire relative to said contact for any position of the contact comprising a rotatable member having a pin projecting eccentrically therefrom, a slot in said support receiving said pin, and stationary means to mount said rotatable member whereby rotation of said member will change the position of said pin and thereby change the position of said support.

15. In a recording instrument, a recording mechanism movable from a non-recording position to a recording position, means to shift said mechanism through a path to a point corresponding to the value of a condition, a deflecting member frictionally connected to move with said mechanism to either side of a neutral position depending upon its direction of movement in said path, said member being formed with a V-shaped notch and an extension on one side thereof, a constantly rotating cam having a portion moving through said notch to periodically return said member to its neutral position, a pawl pivoted on said cam at a point following said portion thereof, said pawl having a pair of projections to engage said extension and be moved to one position if said member has moved out of its neutral position, said pawl having a third projection to engage said extension and be moved to a second position if said member remains in its neutral position, a crank rotatable coaxially with said cam, a driving pin on said crank to be engaged and driven by said pawl in its second position, an oscillating lever to move said recording mechanism from non-recording position to recording position and back again, said lever having a cam slot therein, a portion on said crank engaging said slot and operative to oscillate said lever upon rotation thereof, a shaft upon which said crank is mounted, a second cam on said shaft, and force applying means bearing on the surface of said second cam to retard rotation of said second cam as the radius of the second cam increases with respect to the point of application of said force applying means to help rotation of the second cam as the radius of the second cam decreases with respect to the point of application of said force applying means.

16. In a multiple recording instrument, a recording mechanism, means to move said mechanism through a path to a position corresponding to the value of a condition, a member frictionally moved around an axis by said mechanism, as the latter moves, to either side of a neutral position a rotating cam having a plurality of lobes cooperating with said member to return the same to neutral position each time one of said lobes moves past said member, driving means mounted on said cam in a position to follow each lobe as the cam rotates, said driving means each including parts cooperating with said member to be moved by said member into or out of an opera-

tive position on said cam depending upon whether said member has or has not remained in its neutral position, a crank mounted on said shaft for rotation therewith, a driving pin on said crank engaged by one of said driving means when the latter is in its operative position, an oscillating lever to actuate said recording mechanism, said lever having a cam slot therein, a part on said crank to engage said slot and oscillate said lever as the crank rotates, and means acting on said shaft to oppose rotation of said crank by said driving means during a portion of the rotation thereof, said last means helping rotation of said crank by said driving means driving the remainder of each rotation thereof.

17. In a recording instrument, a recording mechanism movable from a non-recording position to a recording position, means to shift said mechanism through a path to a point corresponding to the value of a condition, a deflecting member frictionally connected to move with said mechanism to either side of a neutral position depending upon its direction of movement in said path, said member being formed with a V-shaped notch and an extension on one side thereof, a constantly rotating cam having a portion moving through said notch to periodically return said member to its neutral position, a pawl pivoted on said cam at a point following said portion thereof, said pawl having a pair of projections to engage said extension and be moved to one position if said member has moved out of its neutral position, said pawl having a third projection to engage said extension and be moved to a second position if said member remains in its neutral position, a crank rotatable coaxially with said cam, a driving pin on said crank to be engaged and driven by said pawl in its second position, and an oscillating lever to move said recording mechanism from non-recording position to recording position and back again, said lever having a cam slot therein, a portion on said crank engaging said slot and operative to oscillate said lever upon rotation thereof.

18. In an electrical measuring instrument of the self-balancing potentiometer type including a slide-wire and a plurality of resistances, a frame, a casing extending across said frame and mounted on the same, supporting means in said casing, means to mount said resistances on said supporting means, means to adjustably mount said slide-wire on the bottom of said casing, a contact to be moved along said slide-wire, means to move said contact including a recording carriage upon which said contact is mounted, means to mount said recording carriage for movement across said frame, said adjustable mounting means including means to shift said slide-wire relative to said contact for any position of the contact comprising a rotatable member mounted on said casing, and cooperating means between said rotatable member and said slide-wire.

19. A self-balancing measuring instrument comprising a normally balanced electrical circuit which is unbalanced in one direction or an opposite direction in response to variations in the value of a condition, mechanism operative to assume a position corresponding to the value of the condition, exhibiting means movable through a path to a position corresponding to the value of the condition, rebalancing means for said circuit and including a cable drum formed of two relatively adjustable parts, a cable connecting said mechanism, said exhibiting means and said cable drum, the ends of said cable being con-

nected respectively to said parts, a movable pulley over which said cable extends, and means for biasing the pulley in one direction to place a tension in the cable, whereby relative adjustment of the two parts of the cable drum adjusts the tension in the cable.

20. In a self-balancing recording instrument, the combination of a normally balanced electrical circuit adapted to be unbalanced in one direction or an opposite direction in response to variations in the value of a measurable condition, mechanism operative to assume a position corresponding to the value of a condition, a recording means having an operative and an inoperative position movable through a path to a position corresponding to the value of a condition, circuit rebalancing means, a cable connecting said mechanism, said recording means and said rebalancing means whereby upon operation of said mechanism said circuit will be rebalanced and said recording mechanism will be moved to a point in its path corresponding to the value of the condition, a pulley over which said cable passes and which is rotated thereby, a member frictionally driven by said pulley to a position on either side of a neutral position, a constantly rotating cam operable to periodically return said member to its neutral position upon departure therefrom, a pawl pivoted to said cam and adapted to move into one of two positions, said member having a portion lying in the path of said pawl to engage said pawl and move it to one position when said member is deflected and to engage said pawl and move it into its other position when said member is in its neutral position, means including a rotatable crank and a lever oscillated by said crank to be operated by said pawl when the latter is in its other position, and means actuated by said oscillating lever to move said recording mechanism from its inoperative position to its operative position and back again.

21. A multiple recording instrument comprising in combination, a device to make consecutive recordings on a chart of the values of a plurality of physical conditions at a position of said device corresponding to such values, even though said values vary so that consecutive recorded values differ substantially from each other, at time intervals depending upon the difference between said values and a given time interval or said given time interval and a fraction thereof, means to move said device across the chart to a position to make a recording, testing means having a cyclically operating portion of a period equal to a fraction of said given time interval for testing such correspondence, and an element moved by said testing means operative to produce a recording operation by said recording device if said recording device has reached such correspondence within said time interval after a previous recording operation, or said time interval plus a fraction thereof if said recording device reaches such correspondence after the end of said given time interval after the preceding recording operation.

22. A multiple recording instrument comprising in combination, recording means moved through a path consecutively to a plurality of positions each corresponding to the value of a physical condition, an instrument for moving said means through its path to such positions at a speed whereby a given distance will be covered in a given time interval, cyclically operating testing means to determine if said recording means

has reached a position of correspondence, said cyclically operating means having a period shorter than said given time interval, mechanism to operate said recording means at the end of each given time interval if said recording means has reached said position of correspondence in said time interval or to operate said recording means after said given time interval plus one or more of said periods of said testing means determined by when said position of correspondence is reached, and means to operate said mechanism from said testing means.

23. In a multiple recording instrument, a recording carriage having a recording member thereon movable from operative to inoperative position, an instrument for moving said carriage through a path to different positions corresponding to the values of a plurality of physical conditions, said means moving said carriage through said path in a given time interval, cyclically operating testing means having a period of operation which is a fraction of said given time interval for determining if said carriage has reached a position of correspondence, means operatively connected to said testing means to move the recording means from inoperative to operative position after a predetermined number of said periods if said carriage has reached a position of correspondence as determined by said testing means if said position is not more than a given percentage of said path of travel from the previously recorded position of correspondence, or if said carriage moves through a larger percentage of its path than said given percentage at the end of any period after said position of correspondence is reached.

24. In an intermittently operable recorder, the combination of a marker for a chart, means for governing the position of said marker across the chart in correspondence with the value of a physical condition, a device for causing the marker to record its position on the chart at times spaced at intervals of not less than X seconds each, means operatively connected to said governing means to test said correspondence during a cycle of X/N seconds, and means operatively connected to said testing means for operating the marker at the end of each period of X seconds if the position of correspondence has been reached in that time, if said position of correspondence has not been reached operating said marker after X seconds plus X/N seconds or a plurality of X/N seconds after said correspondence has been reached, N being an integer larger than unity.

25. In an intermittently operable recorder, the combination of a marker for a chart, means for governing the position of said marker across the chart in correspondence with the value of a physical condition, a device for causing the marker to record its position on the chart at times spaced at intervals of not less than X seconds each, means operatively connected to said governing means to test said correspondence during a cycle of X/N seconds, and for operating the marker at the end of each period of X seconds if the position of correspondence has been reached in that time, if said position of correspondence has not been reached operating said marker after X seconds plus X/N seconds or a plurality of X/N seconds after said correspondence has been reached, N being an integer larger than unity, said means operatively connected to said governing means including a member deflecting on either side of a neutral position de-

pending upon the direction of movement of said marker, and said means for testing including a constantly rotating element operative to periodically return said member to its neutral position, a part carried by said element and having two positions, means to hold said part in either one of said positions, said member including a portion to engage said part and move it into one or the other of said positions depending upon whether or not said member remains in its neutral position after it has been returned to that position, and mechanism operated by said part to operate said marker.

26. A multiple recording instrument comprising in combination, a device to make a record on a chart of the values of a plurality of physical conditions, means to move said device across the chart to positions corresponding to the value of the conditions, testing means having a given period of operation to test whether or not said device has reached said position of correspondence, an element moved by said testing means to operate said device and drive means between said testing means and said element operative to move said element after a given interval of time equal to a plurality of said given periods of said interval and at least one of said periods.

JOHN A. CALDWELL.
